United States Patent Office

Des. 192,855
Patented May 22, 1962

192,855

LOUNGE CHAIR

John P. Mengel, 1401 N. Dearborn Parkway,
Chicago, Ill.

Filed Sept. 5, 1961, Ser. No. 66,614

Term of patent 14 years

(Cl. D15—11)

FIG. 2

FIG. 3

FIG. 4

FIGURE 4 is a rear elevational view of the chair shown in FIGURES 1, 2 and 3; and

I claim:

The ornamental design for a lounge chair, substantially as shown.
